UNITED STATES PATENT OFFICE

2,616,216

DOLL

Edward Fraysur, Winchester, Ky.

Application January 10, 1947, Serial No. 721,175

3 Claims. (Cl. 46—120)

1

This invention relates to dolls, and more particularly to a mechanical doll having provisions, arrangements and mechanism for simulating going to sleep, awakening and accompanying sounds and movements of the limbs, and with substantially the same effects and occurrences as with a natural live infant.

This application is a continuation in part of my application Serial No. 648,622, filed February 19, 1946, now Patent No. 2,565,603.

The special objects and advantages to be attained will be hereinafter more fully explained in connection with the accompanying drawings illustrative of a practical, but non-limiting embodiment of the invention, in which:

Figure 1 is a view partly in longitudinal section and partly in elevation of a doll structure having provisions, arrangements and mechanism therein according to the present invention.

Figure 2 is an enlarged detail view of the power spring and gearing for operating the eyelids.

Figure 3 is an elongated side elevational view with portions broken away of the spring-operated crank for actuating the arms and legs of the doll.

Figure 4 is a top plan view of the doll with a portion of the body broken away to show the operating parts therewithin and looking down upon the top of the same.

Referring now to the figures, 10 represents the main body portion of the doll which is hollow and made of any suitable rigid material, or at least semi-rigid and form-retentive in character, and having a head portion 11 also hollow. Between the body and head portions is a neck portion 12 also hollow to afford a communicating opening of ample size between the body and head portions.

Legs 13 and arms 14 are constructed so as to have at least limited movement, although they are integrally attached to the body portion 10. Both the legs and arms are hollow to accommodate operating connections. They are preferably constructed of resilient material, but are generally form-retentive in character. However, at the crotch portion where the inner and outer portions of the legs and arms may be bent, the crotch portions are reduced somewhat in thickness as at 82, to permit readily the bending of the legs or the arms. If desired, the legs and arms may be made in articulated or hinged-ly-connected sections.

Associated with the openings in the head 11 for eyes 15 are curved and dished lids 16 which are fixed to one end of a lever 19 which is pivotally mounted at 17 within the head, Figure 1.

2

The pivot 17 comprises a common transverse part or shaft pivotally supported at its opposite ends in the opposite side walls of the head.

The other end of lever 19 extends from the pivot 17 and is pivotally attached, as at 20, to a link 21. The link 21 may be made of a piece of stiff wire and provided at its free end and at a point intermediate its ends with stop portions 22 and 23 formed by looping the link into eye formations. These stop portions, however, may be formed in any other suitable manner. Within the body 10 is fixed a supporting frame 24 to which the various mechanisms for effecting the operation of the eyelids and the legs and arms are connected. Pivoted to the near end of supporting frame 24, as at 25, is a long lever 26 connected by an eye formation 27 thereon with the link 21 to operate between the stop portions 22 and 23. By this provision and arrangement of the lever 26, and with the lever 26 in the position shown in Figure 1, in which position the eye portion 27 is in contact with the stop portion 23 of the link 21, the link 21 has been moved to a position whereby the eyelid 16 is positioned to cover the eye 15. However, when the lever is tilted on its pivot 25, and its end portion which cooperatively engages the link 21 is raised, the lid 16 is moved to uncover the eye 15. At times during the pivotal movement of the lever 26 between the full opening and closing positioning of the lid 16 there is considerable lost motion between the stop portions 22 and 23 on the link 21, whereby the lid 16 remains in either its opened or closed position during these parts of the rocking movement of the lever 26. The portion of the lever 26 within the body 10 normally rests upon a pin 31 carried by a control gear 32, such portion of the lever 26 having a transversely extending cam 28' and an outwardly bent release 29 which slips over the pin 31 during each revolution of the gear. The lever 26 is held normally in contact with the pin 31 by a spring element 28 connecting the opposite end portion of the lever 26 with an adjacent wall portion of the doll body and as shown in Figure 1, the spring connection between the lever 26 and the doll body is in the region of the neck portion of the body 10.

On the supporting frame 24 is a longitudinally slidable carriage 33 guided by pins 34 on the frame and extending through elongated slots 35 of the carriage. This carriage 33 may be worked by either one of the two weights 36 or 37 pivoted respectively at the upper end and side of the supporting frame 24.

The weight 36 is pivoted as indicated at 38, and when rocked, as by movement of the doll transversely back and forth, will act through linkage 39 to move a transversely extending slide 41 up and down. This slide has a roller 42 co-operating with one end of the carriage 33 and acting upon an inclined track 43. Accordingly, as the roller 42 is moved up and down on the track 43, the carriage 33 will be reciprocated longitudinally along the supporting frame 24.

As the doll is rocked by tilting the doll up and down, the weight 37 pivoted at 44 to the side of the frame 24 will act through a pin 45 on the carriage 33 to effect a similar reciprocation of the carriage 33. A return spring 46 will return the carriage to its original position.

The carriage 33 has two dogs 47 and 48. The dog 47 acts upon a ratchet wheel 49 to which is connected a pinion gear 50 for rotation therewith, the gear 50 being in meshing engagement with the control gear 32 bearing the pin 31. The gear 32 has on its side opposite from the pin 31 a plurality of circumferentially spaced pins 51 extending laterally therefrom. These pins 51 are adapted to engage in succession a crank arm 52 having a pawl 53 acting upon a ratchet 54 to cause the tightening or winding up of a spring within the housing 55 of a spring motor, Figure 2. The spring motor is indicated by the reference numeral 56. The crank arm 52 is returned to its original position after a pin 51 has passed by a return spring 57 to bring the arm 52 against a stop 58.

This spring motor 56 acting through a gear train 59 will cause rotation of a pinion 61 having abutment means or three laterally extending pins 62. This pinion 61 will be rotated slowly and as one of its pins 62 abuts a second or pivoted lever 63 on the supporting frame 24 it causes the lever 63 to move laterally. The lever 63 will act upon the cam 28' to move the lever 26 laterally and off the pin 31 so that the lever 26 will pivot in a clockwise direction under the action of the spring 28 whereby to effect an opening of the eyelids 16.

When the lever is in its down position, and in order for the pin 31 to be moved to the under edge of the lever to again raise the lever 26, the pin will pass downwardly through the recess 29 of the lever so as to gain access to the under edge thereof. As the gear 32 continues to rotate, the lever 26 will be bodily raised by the pin 31 so as to again be put in a position whereby it can be released by the lateral movement of the lever 63. During this time the doll will have its lids closed and they will remain closed to simulate sleeping until a later time when the lever 63 again acts upon the cam 28'. This length of time is dependent upon the ratio of the various gears connected to or with the spring motor 56.

Connected with the lever 26 is a rod 64 bent over the supporting frame and its upper end extending down in the rear of the supporting frame 24 for connection with a bellows arrangement which gives forth a loud vociferous sound in simulation of an infant when startled or suddenly awakened. It will be noted that this takes place at the same time that the lids are opened by the clockwise rotation of the lever 26.

In order at this time that the doll will effect a kicking of the legs and arms to further show that it is awake there is provided a second spring motor 66 which is tightened or wound up by the dog 48 of the carriage 33. This dog 48 acts upon

5 a ratchet 67 to rotate the same in a counter-clockwise direction. The ratchet 67 is held in a position to which it has been rotated by the dog 48 by a retaining dog 68 held in engagement with the ratchet 67 by a spring 69. Should the spring motor 66 be wound up to its full extent its clutch portion 71 will leave the projection 72 whereby the spring 66 will not at any time be tightened to cause its breakage. Extending from the spring motor 66 is a square shaft 73 adapted to operate a ratchet wheel 74 and a crank 75 connected to the wheel, as indicated at 76. This crank 75 connects with one side of the third lever 77 so as to oscillate the lever 77 to give actuation of the legs and arms 13 and 14 respectively through the connections with the opposite ends of the lever 77 as by cables 78 and 79. Each cable 78 is connected to the foot portion of the leg, as indicated at 80, and extends through an eye 81 adjacent the knee of the leg. The foot portion 80 will be raised and can be returned by the natural resiliency of the leg.

20 Each cable 79 extends through an eye 83 and from there on into the arm 14. The connection of the cables 78 and 79 to the lever 77 can be effected in any manner desired. One leg and one arm can be connected to one side of the lever or both arms or both legs can be connected to one side of the lever.

25 In order that the actuation of the arms and legs will be sent into motion simultaneously with the release of the lever 26, there is provided a fourth or pivoted lever 84 having one end pointed as indicated at 196, for engagement with a driving ratchet 74. The other end of the lever 84 is provided with a projecting lug which underlies the free end of the lever 26. As the lever 26 drops down, it will engage the lug 85 of the lever 84, whereby to release the driving ratchet 74 and permit its rotation so as to effect the actuation of the legs and arms. The lever 84 remains out of engagement with the ratchet 74 until, by rocking the doll, the pin 31 carried by the control lever 32 lifts the lever 26, allowing pointed end 196 to again engage ratchet 74 and stop its rotation. Upon continued rocking, the lever 26 is again moved laterally and off the pin 31, resulting in the opening of the eyelids 16 and actuation of the arms and legs. In the absence of rocking thereafter, the arms and legs will move, with the eyes open, until the spring motor 66 has run down.

30 It should now be apparent that there has been provided a doll wherein simulation of sleeping and awakening, as well as voice, can be had.

35 While various changes may be had in the details of the construction, it should be understood that such changes shall be within the spirit and scope of the present invention as defined by the appended claims.

40 I claim:

45 1. A simulated sleeping doll comprising a body having a head provided with openable and closable eyelids, a supporting frame secured longitudinally within said body, a carriage disposed longitudinally of said frame and mounted on the latter for reciprocatory movement therealong, a slide arranged transversely on said frame adjacent one end thereof and connected to said supporting frame for transverse back and forth movement thereon, a first weight arranged in parallel spaced relation with respect to said slide and pivotally connected to said one end of said frame for lateral swinging movement, a second weight arranged longitudinally of said frame

intermediate the ends of the latter and pivotally connected to said frame for longitudinal swinging movement, connecting means between said second weight and said carriage whereby swinging of said weight reciprocates said carriage, an inclined track on said carriage contiguous to said one end of said frame, a rotatable roller on said slide intermediate its ends and engageable with said track whereby said carriage is reciprocated longitudinally by transverse reciprocation of said slide, connecting means between said first weight and said slide for causing said slide to reciprocate as said first weight swings, a lever arranged longitudinally of and rockably supported intermediate its ends on said frame and having one end operatively connected to said eyelids for effecting a closing movement of the latter upon rocking movement of said lever in one direction and an opening movement of the same upon rocking movement of said lever in the opposite direction, a cam on said lever adjacent the other end thereof, a control gear rotatably supported on said frame and having means normally in engagement with said lever for effecting the rocking movements of the latter upon rotation of said control gear, a dog secured to said carriage, ratchet mechanism connecting said dog to said control gear to rotate the gear unidirectionally as the carriage reciprocates, a spring motor wound by said control gear, a pinion rotatably supported on said frame and connected with said spring motor for rotation thereby, abutment means on said pinion, and a second lever arranged laterally of said first named lever adjacent the other end of the latter and pivotally connected intermediate its ends to said frame and having one end engageable with the abutment means on said pinion and having the other end engageable with the cam on said first lever to disengage said first lever from said means on said control gear.

2. A simulated sleeping doll comprising a body having a head provided with openable and closable eyelids and movable legs and arms, a supporting frame secured longitudinally within said body, a carriage disposed longitudinally of said frame and mounted on the latter for reciprocatory movement therealong, a slide arranged transversely on said frame adjacent one end thereof and connected to said supporting frame for transverse back and forth movement thereon, a first weight arranged in parallel spaced relation with respect to said slide and pivotally connected to said one end of said frame for lateral swinging movement, a second weight arranged longitudinally of said frame intermediate the ends of the latter and pivotally connected to said frame for longitudinal swinging movement, connecting means between said second weight and said carriage whereby swinging of said weight reciprocates said carriage, an inclined track on

said carriage contiguous to said one end of said frame, a rotatable roller on said slide intermediate its ends and engageable with said track whereby said carriage is reciprocated longitudinally by transverse reciprocation of said slide, connecting means between said first weight and said slide for causing said slide to reciprocate as said first weight swings, a lever arranged longitudinally of and rockably supported intermediate its ends on said frame and having one end operatively connected to said eyelids for effecting a closing movement of the latter upon rocking movement of said lever in one direction and an opening movement of the same upon rocking movement of said lever in the opposite direction, a cam on said lever adjacent the other end thereof, a control gear rotatably supported on said frame and having means normally in engagement with said lever for effecting the rocking movements of the latter upon rotation of said control gear, a first dog secured to said carriage, ratchet mechanism connecting said dog to said control gear to rotate the gear unidirectionally as the carriage reciprocates, a spring motor wound by said control gear, a pinion rotatably supported on said frame and connected to said spring motor for rotation thereby, abutment means on said pinion, a second lever arranged laterally of said first named lever adjacent the other end of the latter and pivotally connected intermediate its ends to said frame and having one end engageable with the abutment means on said pinion and having the other end engageable with the cam on said first lever to rotate the gear unidirectionally as the carriage reciprocates, a second dog on said carriage, a second spring motor wound by said second dog, a ratchet carried by said second spring motor, a third oscillatable lever operatively connected to said ratchet and cable means connecting said arms and said legs to said third lever.

3. A doll according to claim 2 including in addition a fourth lever pivotally supported on said frame and having one end engageable with said ratchet and having the other end provided with means underlying and engageable with the other end of said first lever.

EDWARD FRAYSUR.
